Attorney.*

UNITED STATES PATENT OFFICE.

ALBERT LUDWIG, OF BERNBURG, GERMANY.

VESSEL FOR THE RECEPTION OF HIGH-PRESSURE GASES.

SPECIFICATION forming part of Letters Patent No. 699,333, dated May 6, 1902.

Application filed October 3, 1900. Serial No. 31,872. (No model.)

To all whom it may concern:

Be it known that I, ALBERT LUDWIG, a subject of the Emperor of Germany, residing at Bernburg, Anhalt, in the Empire of Germany, have invented certain new and useful Improvements in Electric Furnaces for Gases Under High Pressure, of which the following is a specification.

Apparatus as hitherto constructed for the reception of gases and adapted for the heating of substances within an atmosphere of high-pressure gases—such, for example, as used for the production of artificial diamonds—are usually provided with screw-covers which are not adapted to secure a perfectly-tight joint. The difficulty in providing a tight joint is due to the uneven stresses upon the screws of the cover. Escapes are particularly observable when working with very light gases and with pressures exceeding one thousand atmospheres. In cases where it is required to heat substances permanently by electricity in an atmosphere of high-pressure gases and at the same time intensely cool the containers the screwed covers are unsuitable.

The object of this invention is to provide a reliable and thoroughly gas-tight closing device for vessels or metal cylinders containing gases under high pressure, and, further, also, to provide a refrigerator adapted to effect a radial pressure upon the external cylinder-surface, so as to effectually counteract the expansion and consequent permeability of the cylinder-wall due to the heat and the gas-pressure.

In the accompanying drawings, Figure 1 shows a vertical section taken substantially upon the lines A B of Fig. 3. Fig. 2 is a side elevation with the retaining-strap broken away. Fig. 3 is a sectional view taken substantially upon the line C D of Fig. 1; and Fig. 4 is a view of the valve-stem, partly broken away.

A hollow metal cylinder *a* is provided upon the reduced portion of its outer surface with ring-plates *b* for strengthening and cooling it, the various rings being firmly connected together by means of screw-bolts and nuts *b'*. The rings are formed with recesses *c*, which by passages *z* are in communication with each other and which serve as cavities for the re-

ception and flow of cooling liquid passing through *d* *d'*. By reason of the contraction of the rings through the cooling they produce strong pressure in a radial direction upon the metal cylinder.

The metal cylinder *a* is formed with a convex bottom *e*, which reposes in a suitably-shaped support *f* in connection with a metallic strap *g*, composed of numbers of plates firmly secured together by bolts *g'*. Within the opening in the hollow cylinder *a* are placed the carbon or other electrodes *v w* for forming the electric arc, the lower one being connected with the metallic cylinder and the upper one with the spindle *m*.

The metal cylinder *a* carries at its upper portion the cover *h*, to which is secured a gas-inlet nipple *k*, a gas-regulating valve *i*, and the electrode-regulating device. The inlet-nipple consists of a suitable tube *k*, which connects with the recess containing the valve-stem *i* and with a suitable opening leading to the interior of the furnace. The valve-stem *i* has an orifice, which in the well-known manner in the use of gas-cocks is adapted to complete said openings by a partial turn of the stem to admit gas. The electrode-regulating device consists of a rotatable spindle *m*, which at its reduced inner end carries a flexible suspension *p*, which supports the upper electrode. By turning the spindle *m* the height of the electrode is regulated. The cover, the upper portion of which forms a convex surface *e'*, fitting a correspondingly-shaped metal block *f'*, is pressed against the aperture of the metal cylinder *a* by slightly-tapering wedges *n n'*, driven between the strap *g* and the metal block *f'*, provided upon the cup of the cover *h*.

In most cases it will be found sufficient to firmly drive in the wedges *n n'* without having to heat the strap *g*, and the apparatus can be so mounted in a few minutes as to enable it to support a pressure of several thousand atmospheres without leaking. If, however, gases of low density are utilized, it may often become necessary to heat the strap and to tighten the wedges *n n'*. After the strap has cooled it produces a pressure upon the wedges *n n'* and upon the cover and cylinder sufficient to close all the pores. By reason of the concentric relation between the metal cylinder and cover and the convex surfaces *e*

and e' said cover and cylinders will assume automatically a central position in the strap g , and a uniform pressure is exerted between all parts of the closing piece or cover and the cylinder. If the wedges $n n'$ are provided with division-lines or graduations, it will be easy to exactly regulate the pressure at which it is desired the gases or the liquid should escape from the joint o of the metal cylinder a 10 by appropriately setting the wedges after slightly heating the strap to correspond to such pressure, which naturally must be within the safety limits of the apparatus. It is clear that the more firmly the wedges are driven in 15 the more safe will be the joint, while, however, a certain definite maximum pressure may not be exceeded. By then measuring each time the existing pressure and marking the corresponding positions of the wedges to 20 each other it will obviously be easy afterward to adjust the said wedges in advance to any desired maximum pressure, and in this manner it is possible to standardize other pressure-gages in communication with the cylinder a to thousands of atmospheres. The elastic strap g , preferably constructed of lamellar plates g' , fixed by the wedges $n n'$, expands 25 at the required pressure and allows the gases or liquids to escape at the point o , so that a 30 special safety-valve is not required.

For fixing the pipe connections, current-inlets, valve-spindles, &c., the ordinary screws, which may be torn out by the high pressure in the vessel a , and which therefore are always a source of danger when working with 35 high-pressure gases, may be replaced by a similar strap-and-wedge arrangement in the following manner: The flange h of the cover, which is recessed at the parts where the connections i , k , and m pass through, is turned down at its outer periphery to receive the ring y , which is fixed by means of screws y' after first having placed the spindles and tube connections i , k , and m , with covering-caps 40 q , bushings q^2 , and packing material q' , into the aforementioned recesses, as shown in Fig. 1. Thereupon between the bushings q^2 and caps q the wedges $s s'$ are driven, the one, s , formed with a nose, taking beneath lower 45 surface of the turned portion, while s' can be tightly fixed by means of bridge-pieces and screw-nuts t . Leakage and disruption of the joints is thus effectually prevented. The cover may be utilized as a safety means against 50 excess of pressures, as above explained, by regulating the same in driving in the wedges $s s'$ to a more or less degree. Thus in omitting almost all screws the apparatus, besides

insuring against leakage, which is particularly of importance for light gases—such as, 60 for instance, hydrogen—has the advantage of being free from danger.

Having thus described my invention, what I claim, and desire to secure by Letters Patent, is—

1. An electric furnace for gases under high pressure, comprising a vessel having a cover, a fastening-strap inclosing the same, wedges adapted to force the parts together, means to hold the vessel and cover centrally within 70 the strap and to allow self-adjustment so that a uniform pressure is transmitted to all portions of the apparatus, and means for producing an electric arc within said vessel, substantially as described.

2. An electric furnace for gases under high pressure, comprising a metallic vessel having a cover and concave surfaces, a fastening-strap inclosing the same, wedges adapted to force the same together, recessed blocks adapted to receive said concave surfaces, and means for producing an electric arc within said vessel, the arrangement being such as to allow of self-adjustment centrally and the transmission of a uniform pressure to all parts of 85 the apparatus, substantially as described.

3. An electric furnace for gases under high pressure, comprising a vessel having a cover, a fastening-strap inclosing the same, wedges adapted to force the cover upon said vessel, 90 graduations upon said wedges whereby the parts may be adjusted to allow gas to escape at a predetermined pressure, means to hold the vessel and cover centrally within the strap and to allow self-adjustment so that a 95 uniform pressure is transmitted to all portions of the apparatus, and means for producing an electric arc within said vessel, substantially as described.

4. An electric furnace for gases under high 100 pressure, comprising a vessel having a cover, a fastening-strap inclosing the same, wedges adapted to force the cover upon said vessel, a refrigerating device for said vessel comprising rings shrunk upon said vessel to produce 105 a predetermined external pressure, means for cooling said rings, and means for producing an electric arc within said vessel, substantially as described.

In testimony whereof I have hereunto set 110 my hand, in presence of two subscribing witnesses, this 18th day of September, 1900.

ALBERT LUDWIG.
